UNITED STATES PATENT OFFICE.

ERNEST A. LOWE, OF NORTH PLAINFIELD, NEW JERSEY, ASSIGNOR TO LOWE MANUFACTURING COMPANY, OF PLAINFIELD, NEW JERSEY, A CORPORATION OF NEW JERSEY.

FIRE-DOOR-RELEASING MECHANISM.

1,269,556.

Specification of Letters Patent. Patented June 11, 1918.

Application filed June 17, 1913. Serial No. 774,101.

To all whom it may concern:

Be it known that I, ERNEST A. LOWE, a citizen of the United States, and a resident of North Plainfield, in the county of 5 Somerset and State of New Jersey, have invented certain new and useful Improvements in Fire-Door-Releasing Mechanism, of which the following is a specification.

My invention relates to releasing mechanism 10 automatically controlled through changes of temperature and serving to bring about the automatic closing or opening of a gate or barrier in a passage or opening of any kind.

For the sake of illustration, however, my 15 invention will be described with reference to a door located in a partition and designed to automatically close on the occurrence of fire.

My invention however is not confined to 20 use with "doors" in the limited sense of the term but may be applied to windows, shutters, or other devices, and to such devices when normally closed and caused to open 25 automatically on the occurrence of fire, as is sometimes required in order to allow the escape of smoke, as for instance in the well of a fire escape, or to divert a draft of air.

Ordinarily such doors are held open normally 30 by the use of a counterbalance weight attached to the door, thus allowing the door to move freely or to be held readily in any position, whereby said door may be employed in the usual way of doors and opened 35 or closed at will by anyone desiring to pass through the opening.

To avoid danger from fire arising from the door being left accidentally open, the ordinary practice heretofore has been to add 40 a protective device consisting of a fusible link connected to a cord, by which the counterbalance is sustained, so that in case of fire the melting of the link will release the rope and allow the counterbalance to fall or be 45 come disconnected from the door, thus allowing the door to respond to the action of gravity and to close.

This fusible link protection is the source of a great deal of criticism as, being a fixed 50 temperature device, it will not act until the temperature reaches a certain maximum, which means the fire is under great headway directly at the link with the grave possi-

bility of the fire communicating through the open doorway before the link operates 55 and the door closes; in fact this is what happens in the majority of times, and to insure the positive releasing of the weight and the closing of the door while the fire is in an incipient stage, or before it has attained headway necessary to fuse the link is one of the purposes of this invention.

To accomplish it, advantage is taken of the well known property of air to expand when heated. As air has a definite coefficient 60 of expansion per degree of temperature rise, this device, instead of depending for its operation upon the temperature to reach a certain maximum, such as the fusible link or fixed temperature device does, is made to 65 operate when the temperature rate per minute advance reaches a certain minimum without regard to initial or maximum temperature. In other words, a "rate of rise" instead of a "fixed temperature" principle 70 is employed for its operation. As the presence of fire causes the temperature to advance very rapidly per minute and far above the advance from any local cause, such as light, heating, atmospheric, or manufacturing, it is obvious that the "rate of rise" temperature device needs only to have 75 a compensating device making it respond only to that "rate of temperature rise" over and above the temperature advances from 80 abnormal local conditions to have the device operate only from fires and not from temperature advances caused by other conditions, and this is exactly what this new invention does in practice.

This compensating device consists of a relief vent leading from the air-chamber and having a predetermined leak adjusted to relieve the pressure in the air-chamber up to any predetermined pressures caused 85 by certain rates of temperature rises, but not to relieve that pressure arising from rates of temperature advance caused by fires, which are very excessive and violent. The difference between rates of temperature advances from fires and local or ordinary heating are shown by the experiments and tests made by the National Board of Fire Underwriters, showing that a four-degree rate of 90 temperature rise safely covers the temperature advances from all local conditions ex-

cept actual fires, when the temperature advance is very marked and violent. I find from actual and continued experiment in practice that fires cause the temperature to 5 advance near the fire from 4 to 100 degrees per minute, according to local conditions and the size and class of the fire. As small a fire as a few sheets of paper, pile of rubbish, or an alcohol fire say 3 feet square will 10 raise the temperature nearby from 25 to 50 degrees per minute. In actual practice with this door release device I find 3 sheets of common newspaper or an alcohol fire 1½ feet square placed 25 feet from the door opening 15 will operate the device in from 25 seconds to 30 seconds. At the same time the device through its compensating feature will not respond to local temperature changes.

These effects and the pressures obtained 20 from the excessive rate of temperature rise caused by fires are converted into the necessary power by the simple means of causing the expanding air in the air-chamber to work against a flexible wall, such as a dia- 25 phragm ready to move when the confined air in the air-chamber expands from the heat of the fire, and to thereby mechanically release anything held in restraint, one of which ways, as herein described, is to me- 30 chanically release a counterbalance weight used to counterbalance a fire door. The air-chamber or air-chambers are preferably so constructed that the inclosed volume of air is readily affected by any change of tem- 35 perature, a favorable form being that of thin metal balls, one or more, connected to a pressure responsive means one wall of which is flexible and yields to the expansion of the air inside. This flexible wall of the 40 air-chamber or diaphragm in its line of travel moves a pin or plunger, which in turn operates or controls the necessary gears or levers so arranged that a weight will be released by the expansion of the confined air.

45 While I prefer to employ an air thermostat such as described, provided with an automatic compensation for normal changes or rates of change of temperature, such as above indicated, it is not to be understood 50 that my invention is limited to such special thermostats, since many of the devices and combinations of devices hereinafter described and shown in the accompanying drawings may be used with other forms of 55 thermostat acting by change of temperature to release the mechanism which permits or causes the door to close.

One of the many forms of construction by which my invention may be carried out is 60 shown in the accompanying drawings.

My invention consists in the construction and combinations of apparatus hereinafter described and more particularly specified in the claims.

65 Figure 1 shows a self-closing fire door

equipped with apparatus constructed in accordance with my invention.

Fig. 2 is an enlarged elevation of a portion of the apparatus.

Fig. 3 is a vertical section on the line 70 3—3 Fig. 4.

Fig. 4 is a plan of the apparatus, the casting being shown in horizontal section.

Fig. 5 is a section through the apparatus on the line 5—5 Fig. 4. 75

Fig. 6 shows a portion of the releasing mechanism detached and in normal position.

Fig. 7 shows the same parts of the mechanism with the parts in released position.

Fig. 8 is a plan and partial section of the 80 apparatus through the chamber containing the diaphragm which responds to the increased pressure of the air when heated in the air-chamber.

Fig. 9 is a detail showing in section the 85 air vent for the air-chamber, whereby a compensation is obtained for normal rates of rise of temperature so that the thermostat will not operate to release the door.

Fig. 10 is a detail showing in section the 90 connection of the air bulbs of the thermostat to the common union or chamber, which in turn communicates with the space containing the diaphragm of the thermostat.

Fig. 11 shows a detail of the operating 95 spring and train of wheels of the clockwork mechanism.

Fig. 12 is a detail view showing a pawl and an arm joined thereto, whereby the devices are freed from the detaining mechanism controlled by the thermostat in case of the breakage of the main spring and are thereby left free to the action of a supplemental spring as hereinafter more particularly described. 100

1 indicates a door adapted to close an opening in the wall 2 and sustained upon inclined ways 3 in the usual manner, so that when left free to the action of gravity it will move and close said opening. 105

4 is a counterweight sustained by the cord 5, which connects at one end with the door, as shown, and passes over a pulley 6 fixed to the wall or other suitable support and around a wheel or pulley 7 carried by the 110 weight. 100 indicates the fusible link connected to said cord and to which reference is heretofore made. The free or opposite end of said cord at 8 is knotted and is sus-

tained in the slot of a pivoted arm 9 forming 115 a slip hold, which, being normally sustained or held by a detent in the position shown in Fig. 2, will prevent the weight from dropping to the floor. When, however, the de- 120

tent is released and the arm permitted to 125 turn downward by the influence of the weight, the cord will slip from its hold in the yoke or hook formed by the arm 9 and the weight 4 will drop to the floor and the door 1 will close, being free from the re- 130

straint of the counterweight, in obvious manner.

The arm 9 is, in effect, a release device immediately associated with the door and which acts to free the same by freeing it from the influence of the restraining device comprising, in this instance, the weight or counterweight, which opposes the continual bias of the weight tending to close the door. Combined with said release device I employ 5 detent mechanism normally holding said release device out of action and comprising preferably a train of detents some of which, near the release device, are preferably constructed to have a self-releasing tendency. The final member of said train or that which is immediately controlled by the rate of rise 10 thermostat is preferably held in normal position by a positive lock or dog which is moved out of the way to free the detent mechanism as a whole by the force of expansion of the air of the rate of rise thermostat when pressure accumulates therein owing to its exposure to a temperature whose 15 rate of rise exceeds the normal or safety rate. Such detent mechanism may be constructed as follows:

10 is a rock shaft to which the arm or lever 9 is secured and with which said arm 20 turns, as on a pivot. A suitable weight 11 may be connected to said arm and rock shaft to cause these parts and the other parts carried by them to be automatically restored to 25 normal position by gravity after release of the door 1. Secured also to the rock shaft 10 is an arm 12 forming the arm of the detent, and which is normally locked in position shown in Fig. 6, by a suitable catch that is caused to free the arm 12 and consequently the weight 4 by the operation of the 30 thermostat and the intermediate mechanisms of any suitable character or form but preferably of the form shown and now to be particularly described.

When the detent arm 12 is so freed, it 35 swings up into the position shown in Fig. 7 under the action of the weight 4 and the knotted end of the cord slips off the hook of the arm 9 and frees the weight in obvious 40 manner.

In the preferred manner of carrying out my invention I employ a second or intermediate trip or detent arm 13 formed as shown more clearly in Figs. 6 and 7 with a 45 shoulder at 14 adapted to form a catch or trip for the end of the detent arm 12. When the detent arm 13 is held against the influence of its spring 15 in position shown in Fig. 6 and the end of the detent arm 12 is 50 engaged beneath the shoulder 14 as shown in that figure, the weight 4 will be sustained; but when the arm 13 is released and allowed to move under the influence of the spring 15, it will turn to position shown in 55 Fig. 7 and release the detent arm 12, which

will thereupon fly up to position shown in Fig. 7 and cause the door 1 to close, if not already in closed position.

The detent arm 13 is mounted upon and turns freely on a second rock shaft 16 and is provided with a pin 17 adapted to be engaged by the arm 18 carried by said shaft. Said shaft 16 is provided with an operating handle 19 which is the re-setting handle for re-setting the mechanism after operation 70 and for likewise rewinding the spring of the spring-driven clockwork or motor shown after each operation thereof. Besides engaging the pin 17 to re-set the detent arm 13, the said arm 18 operates upon other devices to be presently described. 75

The release of the arm 12 by the freeing of the arm 13 to allow the said arm 12 to turn to position shown in Fig. 7, under the influence of the weight 4, and so as to free 80 the same, will be followed upon the release of said weight by the automatic restoration of the arm 12 to position shown in dotted lines in Fig. 7, by the influence of the counterweight 11. Hence, as will be seen, the 85 arm 12 automatically resumes its position for being locked by the detent arm 13 when the latter is thrown back in the re-setting operation to its own normal locked position, such as indicated in Fig. 7 by the dotted 90 line and in Fig. 6 by the full line marking the outline of said part 13. 95

20 is a shaft conveniently designated a master shaft which, or an extension 21 of which, is formed as shown at 22 or in any 100 other suitable manner to act as the detent for normally locking the detent arm 13 when the parts are set. When the shaft is released and permitted to turn in the direction of the arrow Fig. 6, the part 22 assumes the position shown in Fig. 7, thereby 105 releasing the detent arm 13. The resetting of the arm 13 by the re-setting arm 18 acting through the pin 17, which carries the arm 13 to position indicated by the dotted 110 lines in Fig. 7, followed by the re-setting of the shaft 20 to turn the lock 22 back into position shown in Fig. 6, will cause the arm 13 to be locked or detained and the arm or 115 detent 12 to be held in readiness for another operation.

The re-setting of the shaft 20 against the influence of the means tending to turn it so as to free the detent arm 13 is effected by the use of the re-setting handle 19 acting 120 on said shaft 20 through the rock shaft 16, arm 18 and the slotted link 23 that engages by its slotted part a pin 24 projecting from the arm 25 carried by shaft 20 or the extension 21 thereof, as shown in Figs. 7 and 8. 125

The shaft is given a bias in a direction to turn so as to free the arm 13 by means of a spring 26 having one end fixed to post 27 and the other attached to the shaft 20 and said spring is re-set or re-wound by the 130

re-setting of the shaft as just described. The remaining portion of the detent mechanism up to the final member, which is actuated by the rate of rise thermostat, may 5 be constructed as follows:

29 is a gear wheel and 30 a ratchet wheel secured together and adapted to turn freely on the main shaft 20, while 31 is a pawl carried by said main shaft by 10 means of an arm 32 or in any other suitable way, which pawl is adapted to ride over teeth of the ratchet wheel 29 freely when the shaft is turned to rewind the spring, but will engage with a tooth of said 15 ratchet when the spring attempts to unwind and in the unwinding operation. Wheel 30 gears through an intermediate wheel 33 in the manner usually employed in a clock train of wheels or in any other suitable 20 manner with an escapement wheel 34. The retarding escapement 35 or rock shaft carrying the same is provided with an arm or fly 36 bent around or extended for engagement by a detent 37. When engaged by 25 said detent 37 the train and consequently the shaft 20 are locked from movement but when the fly or arm 36 is freed from the detent 37 and the escapement may oscillate freely, the shaft turns with a retarded motion and by the means 22, as already described, controlling the operation of the releasing mechanism for the door, causes said 30 door to close. The detent 37 is upon the end of an arm 38 pivoted at 39 upon a 35 bracket 40 carried by the clockwork frame and is provided with a spring 41, which throws the detent 37 and frees the escapement and shaft 20 when the end of the arm or lever 38 is released from the catch or 40 detent 42, as shown clearly in Fig. 8. The catch or detent 42 might be likewise pivoted, as shown at 43, on a stud of the frame of the apparatus and is itself provided with a spring 44 normally tending to hold it in the 45 position shown in the same figure. One end of the catch or detent lever 42 is engaged by the thermostatically operated pin or plunger 45 and when lifted by said pin or plunger the detent end is drawn down 50 against the influence of the spring 44 and the long arm of the lever 38 is freed, and being acted upon by the spring 41, said lever will move the detent or catch 37 so as to free the arm or rod 36 of the escapement 55 fly. The catch lever 38 is relatched in the position shown in Fig. 8 in any suitable manner but preferably by the action of a hook 46 (see Figs. 3, 4, 5 and 8) mounted upon the arm 18 of the re-setting rock shaft and 60 adapted to engage and re-set the catch or detent 37 and to move the long arm of the lever 38 back over the end of the detent arm 42 and into position where the spring 44 may pull said arm up into position to latch 65 or catch the lever 38 until the recurrence of

the operation of said arm 42 by the thermostatic.

The air thermostat which operates the pin or plunger 45 for the purpose of releasing the power-driven shaft 20 and thereby releasing the door to cause it to close is preferably constructed as follows:

47 indicates sealed metal bulbs of any desired number containing air and communicating through bulb-stems 48 with a 75 common sealed union or air-chamber 49. The rearward extension of the latter is fastened to a frame or support 50, which in turn is secured to the casing 51 or other suitable support. A pipe 52 leads from the chamber 49 or the extension thereof and is joined by the coupling 53 to a pipe 54 leading, as shown more particularly in Fig. 8, from a sealed, flat chamber or casing 55, containing a flexible diaphragm 56 85 clamped between the halves of the casing with an air-tight joint. The plunger 45 is carried by the flexible diaphragm 56, so that when the air in the chambers or bulbs 47 expands and the increased pressure 90 transmitted through the pipes and connections to the lower face of the diaphragm 56 causes the same to bulge, said pin or plunger 45 will act on the latch or detent lever already described and release the detent lever 38, thus freeing the actuating spring 26 and causing the shaft 20 to rotate under the action of said spring.

Communicating with the air-chamber 49 is an air vent of the character already described. This air vent may be mounted in an extension 57 from the air-chamber, the end of which extension being provided with a detachable screw cap 58 sealing the end of said pipe or extension 57 and carrying a 105 vent pipe 59, the inner end of which projects into the air space within the pipe 57. The air vent pipe 59 is preferably packed with air-filtering material, as indicated at 60, and its inner end has its bore or passage 110 restricted in diameter to any desired extent required to determine the rate of escape of air from the chamber when the pressure rises therein, due to the increase of external temperature.

This vent pipe 59 is preferably made of soft metal so that its inner end may be readily compressed or crimped to restrict the air vent or limit the rate of escape of air when the pressure rises. The extent of 120 the leak predetermines the rate of escape and therefore the rate of rise of temperature affecting the bulbs that is necessary to cause the internal pressure to rise and operate the thermostat plunger 45. With an air vent having a comparatively free passage to allow ready escape of air, the rate of temperature rise necessary in order that the diaphragm 56 may be caused to bulge will have to be at a greater rate than would be 125 130 135

the case if the air vent is more compressed so as to more greatly limit or interfere with the rate of escape. In the latter case it is obvious that a lesser rate of rise of temperature and consequent rate of rise of internal pressure will cause the diaphragm 56 to operate. With a normal rate of rise of temperature the air will escape by the vent at a sufficient rate to prevent the internal pressure rising so as to operate the device.

I have shown the air thermostat mounted upon the same frame or support as the mechanism which controls the release of the door but it is obvious that the bulbs 47 and the associated parts forming the air expansion chamber could be mounted in any desired location and coupled by a pipe 54 of the required length with the air-chamber containing the operating diaphragm 56 of the device. The bulbs 47 of any desired number constitute an air heating chamber having heat-conducting walls of large superficial extent, the object being to render the contained air sensitive to changes of external temperature.

My invention, however, is not limited to any particular construction or form of air-chamber for the thermostat and said air-chamber, instead of being composed of one or more bulbs and attached parts, might be of any other desired form.

In order to signal the location of the door which is operated a characteristic signal transmitter suitably connected with the apparatus so as to operate upon the release or movement of the master or controlling shaft 20 is provided. Said signal transmitter is also used as a tell-tale to give warning or notice of accidental breakage of the operating spring 26, which would obviously render the device inoperative and would require that immediate attention be given to restoring the apparatus to working condition. Said signal transmitter may be associated with and brought into action by the operation of the apparatus in any desired manner, but it is preferable to control it directly by the movement of said shaft 20, for which purpose said transmitter may be provided with a trip or release engaged by the arm 25 projecting from shaft 20.

The signal transmitter itself is typified by the spring-actuated signal wheel 61 and contact spring 62 adapted to be engaged by the teeth or projections of wheel 61 and to thereby send the characteristic signal assigned to the particular door or controlling mechanism therefor, indicating its location. The signal may be translated or received on bell 63 or other suitable tell-tale or signal receiving apparatus, as indicated. The release of signal wheel 61, which normally tends to rotate under the influence of its spring, is effected by the release arm 64,

which normally detains the detent arm 65 connected to the shaft carrying the signal wheel. The release lever or arm 64 is arranged in the path of the arm 25 and so that the said arm, on the unwinding or reverse movement of the shaft 20, will release the signal device.

As a measure of safety and in order to insure the operation of the apparatus in case of accidental breakage of the spring 26, pending the repair of the apparatus, the supplemental spring 66 is provided, which acts upon the shaft 20 in the same way as the spring 26. Said spring 66 may be constructed as a spiral spring, one end of which is attached to a fixed post of the frame and the other to the end of the arm 25 secured to the shaft 20. Said spring 66 is under tension and tends to pull the arm 25 over and with it turn the shaft 20 in the same way that the spring 26 turns it when freed from the detaining action of the catch or detent 37.

In order that the shaft may be free to rotate under the influence of the spring 66 in case of breakage of the spring 26, means are provided for freeing the shaft from the detaining action of the fly and detent 37, which is preferably accomplished by uncoupling the said shaft 20 from the clock-work train connecting said shaft with the escapement and fly. For this purpose the pawl 31 which engages the ratchet wheel 29 is provided with a tail-piece or extension 67, which projects over into the space surrounding the spring 26, and so that, when the said spring breaks and expands, its outer layer will engage the tail-piece 67 and lift the pawl out of engagement with the ratchet wheel. This obviously uncouples the shaft from the detaining action of the catch 37 and thermostat, and so that the spring 66 will turn said shaft and produce not only a closing of the door, but by operating the signal transmitter and bell or other tell-tale will give notice of the fact that an abnormal action of the apparatus has occurred, due to the breakage of the spring 26.

The general operation of the apparatus is as follows:

Normally the weight 4 is sustained by the cord 5 which engages the hook 9, the latter being held up by the engagement of the detent arm 12 with the latch or catch 14 upon the detent arm 13, which latter is at such time locked by the lock 22 carried by shaft 20 held in position indicated in Fig. 6 against turning by the action of the spring 26. The shaft 20 is detained from moving under the influence of spring 26 by the catch 37 engaging the fly 36 of the clock train, as already explained, and the catch 37 is itself detained by the latch or catch 42, the diaphragm 56 being at such time relaxed or subject to substantially equal

atmospheric pressure upon its opposite surfaces respectively.

During normal atmospheric changes of air within the air-chamber escapes by the vent at such rate that the pressure will remain substantially equalized and the actuating pin 45 remain depressed. On rapid change of external temperature, due to fire, the pressure in the air-chamber rises rapidly 10 and the internal air pressure is not relieved at a sufficient rate by the air vent to prevent an excess of pressure upon the lower side of the diaphragm 56, which thereupon rises and unlatches the detent arm 38, thus freeing 15 the fly 36, so that the train may rotate by the action of the spring 26 communicated thereto through the pawl 31 and ratchet wheel 29. The shaft 20 now turns under the action of the spring 26 and the 20 part 22 rotates to position indicated in Fig. 7, thus freeing the arm 13, which assumes the position shown in full lines in said Fig. 7 and frees the arm 12. The hook 9 is thereupon freed and the knotted end of the 25 cord slips off its hold on the hook 9, thus freeing the counterweight 4 and leaving the door free to act by gravity and close.

The operation of the parts thus described produces also an operation of the signal 30 transmitter and sends the desired characteristic signal, as already set forth.

When the weight frees itself from the hook 9, the latter, with its rock shaft, immediately resumes the normal position under 35 the influence of the weight 11, so that the arm 12 is restored to position indicated in dotted lines in Fig. 7, its movement to such position not being obstructed by the lever 13, because the latter is at such time in the 40 position shown in the full lines in Fig. 7.

To re-set the parts and rewind the spring 26, as well as to put the spring 66 under additional tension, the re-setting lever 19 is operated, thus operating the arm 18 and the slotted link 23 connected therewith. The first portion of the movement of the slotted arm 23 is a lost motion or without action upon the pin 24 and arm 25, so that the 45 part 22 will temporarily retain the position shown in Fig. 7. During this lost motion, however, of the slotted link 23, the arm 18, by the pin 17, turns the arm 13 from the position shown in full lines, Fig. 7, to, or slightly beyond, the position shown in dotted lines in said figure. When this re-setting 50 movement of the arm 13, which obviously brings it around into position to again lock the arm 12, has been accomplished, the link 23 becomes coupled to the pin 24 at the end of its slot and thereby turns the arm 24 and with it the shaft 20 and part 22 into the position which is shown in Fig. 6, thereby locking the arm 13 in position set. This movement of the arm 55 25 by the action of the arm 18 rewinds the

spring 26 and carries the pawl 31 around to position to engage a fresh tooth or teeth of the ratchet 29, in which position the shaft is held because the spring 26 cannot unwind owing to the detaining action of the parts 70 coupled up thereto through the pawl and ratchet, said detaining parts having been reset at the same time with the re-setting action of the arm 18 upon arms 13 and 25 by the operation of the projection or ear 46 already referred to and carried by arm 18, which, in such re-setting movement, engages the short end of the detent lever 38 so as to carry the detent 37 into position to be engaged by the fly arm 36 and at the same 75 time moves the opposite or long end of the lever 38 back past the end of the catch or catch lever 42, so that it will become latched or engaged by the latter in position shown in Fig. 8.

The re-setting of the signal transmitter or tell-tale is readily accomplished by simply restoring the arm 65 projecting from the signal wheel 61 to position to be latched by the detent arm 64. The parts shown, as 80 will be well understood, merely typify the operating parts of the signal transmitter and do not include the wellknown retarding mechanism employed to retard the unwinding action of the operating spring.

What I claim as my invention is:

1. In an automatic releasing apparatus for fire doors and the like, the combination with the door, of a releasing device, detent mechanism normally holding said releasing device out of action and an air thermostat having an air vent with a predetermined rate of leak and operating by the expansive force of a confined body of air to mechanically free the detent mechanism.

2. In an apparatus of the character described, the combination with a door, of a detent controlled releasing apparatus and a thermostat acting directly and mechanically by the force of expansion of heat upon a 100 detent of said releasing apparatus and adjusted to operate upon any abnormal rate of change of temperature affecting said thermostat.

3. In an apparatus of the character described, the combination with a fire door, or the like, of a release device, a detent normally holding said release device out of action and a rate of rise thermostat having a compensating device adjusted to permit the 115 thermostat to act upon a detent by power of expansion by heat only when the temperature rises at a greater than the normal rate.

4. In an apparatus of the character described, the combination with a fire door 120 normally held out of action, of a fluid thermostat provided with a compensating vent and means controlled by said thermostat for releasing said door.

5. In an apparatus of the character de- 125

scribed, the combination with a counter-weighted door, of sustaining means for said counterweight, a fuse acting in conjunction therewith to sustain the counterweight, a 5 releasing device for releasing the sustaining means, detent controlled mechanism for said releasing device and a rate of rise thermostat for actuating a detent thereof upon change of temperature at an abnormal rate and in 10 dependently of the absolute temperature required to operate the fuse.

6. In an apparatus of the character described, the combination with a counter-weighted door, of detent controlled mechanism for releasing the counterweight, an air thermostat having an air vent and acting by the direct mechanical effect of the expanding body of air therein to mechanically release the detent mechanism and a fuse sus- 15 taining said weight and adapted to free the same on the attainment of an absolute temperature independent of the rate of rise 20

of temperature which brings the air thermostat into action.

7. In an apparatus for automatically releasing doors and the like, the combination with a door and the releasing devices therefor, of two controlling thermostats one an air thermostat having a compensating vent adjusted to cause the same to respond 25 only when the temperature rises at an abnormal rate and independently of the attainment of a fixed temperature, and the other a fixed temperature thermostat consisting of fusible material and adapted to 30 act upon the attainment of a fixed temperature independently of its rate of rise.

Signed at Plainfield in the county of Union and State of New Jersey this 14th day of June A. D. 1913.

ERNEST A. LOWE.
